ABSTRACT

The present invention relates to an apparatus for the storage of a weft thread of specific length in a weaving machine which comprises a rotatable shell wall formed as the generated surface of a truncated cone, and a nozzle for conveying a thread which is to be stored during the weaving process.

APPARATUS FOR THE STORAGE OF WEFT THREADS

BACKGROUND

When weaving with non-conventional weaving machines, more particularly weaving machines wherein the weft threads are introduced by means of a stream of water or air into the shed, the length of thread required for each shot is prepared in a weft thread storage device. In conventional devices used for this purpose, the weft thread length required is stored in the form of a thread loop in a suction tube. A suction tube of this kind has the disadvantage that owing to its length it is cumbersome and inconvenient as regards the space it requires. It does not fit smoothly into a weaving machine.

Instead of storing the weft thread as a loop in a suction tube, it is also already known to use a flow of air to store a thread of given length in a storage container. In this arrangement, the thread is blown into a circular channel-form chamber. With this apparatus it appears that a reliable method of operation cannot easily be achieved without great outlay.

The closest prior art known to applicant in connection with this application is U.S. Pat. No. 3,024,814.

SUMMARY

The present invention is intended to obviate the aforesaid disadvantages. The invention is characterized in that a nozzle is directed towards the inside of a shell wall, and at the place where the base of the truncated cone is situated, there is arranged an end wall which is fixed to the shell wall and comprises in the center an aperture for the exit of the stored thread.

The present invention has the advantages that the stored thread does not undergo any additional twisting. It is also situated in a closed chamber, in which it is protected. Also, the apparatus takes up very little space. When using a storage apparatus with a suction tube, usually a rotating cylinder is used for feeding or dimensioning the quantity of thread to be stored. According to the present invention, this cylinder can be combined with the storage apparatus, which again contributes to the compactness of the apparatus.

BRIEF DESCRIPTION OF THE DRAWINGS

The invention will now be explained in detail with reference to constructional examples of preferred embodiments with reference to the drawings, in which:

FIG. 1 is a view in perspective showing the storage and weft thread feeding arrangement of an embodiment of the invention;

FIG. 2 is a longitudinal view in section through a further embodiment of the invention; and

FIG. 3 is a longitudinal view in section through another embodiment which is used for weaving with various kinds of weft threads.

In all the illustrations, like parts are identified with like reference numerals.

DESCRIPTION OF PREFERRED EMBODIMENTS

FIG. 1 shows a cylindrical arrangement 11 for feeding weft thread and for measuring-off thread sections of predetermined length. The thread 12 is drawn off a supply bobbin 13 and thread sections of measured length are stored in storage apparatus 15. From the latter, they pass through a controllable thread brake 16 to

5 a nozzle 17 by means of which they are introduced into shed 19 through a jet of fluid which is introduced through tube 18. The numeral 20 designates heddles of weaving shafts and 21 is the woven material being produced.

The cylindrical arrangement 11 comprises a cylinder 22 about which the thread 12 is conducted in several turns, being drawn off supply bobbin 13. Each turn is situated also in a groove of element 23. In this way, 10 each turn is clearly separated from the other turns. The cylinder 22 is connected securely to driving surface 24. An arrow 25 indicates the direction in which the cylinder 22 and driving surface 24 rotate.

The storage apparatus 15 comprises a shell wall 30 which is in the form of the generated surface of a truncated cone. Situated at the base of the truncated cone is an end wall 31 which is connected securely to the shell wall 30. The end wall 31 forms a driving surface 24 which abuts on the driving surface 24. Situated at the center of the end wall 31 is an aperture 32 through

15 which the thread 12 can issue. The shell wall 30 and the end wall 31 can be given a rotary movement by a driving means not shown in the drawing. Also provided is an injector nozzle 33. This comprises a duct 34 through 20 which the thread 12 is guided. As indicated by arrow 36, air can be blown into a tube 35 which extends about the duct 34. This air carries the thread 12 with it and conveys it out of the nozzle 33 and towards the internal 25 side of the shell wall 30. The duct 34 comprises a rearwardly directed extension 37 into which the thread 12 enters, being conveyed by rotation of the cylinder 22.

The shell wall 30 is preferably provided with air escape 30 apertures 38 through which the air delivered by the 35 nozzle 33 can escape. The apertures 38 can be round or slot-shaped or of any desired shape. Also, the shell wall 30 can be made, for example, of perforated sheet metal.

In the illustrated example of FIG. 1, a cover wall 39 40 is situated at the top end of the truncated cone defined by the shell wall 30. This cover wall is stationary and is not connected to the shell wall 30, and the nozzle 33 extends through the cover wall 39 and is secured thereto.

45 In operation, the end wall 31 and the shell wall 30 are rotated continuously by the aforesaid driving means which is not shown. At the same time air is blown into the tube 35. Since the driving surface 24 and the end wall 31 abut on one another, the cylinder 22 is also rotated. In this operation, thread is continuously drawn

50 from the supply bobbin 13, since the turns lying on the cylinder 22 are carried along by the cylinder 22. The thread 12 released from the cylinder 22 is drawn by the injector nozzle 33 into the tube extension 37 and blown 55 from the nozzle 33 towards the internal side of the shell wall 30. The nozzle 33 is preferably so directed that the thread 12 is directed towards a region of small diameter of the internal side of the shell wall 30. As a consequence of the rotation of the shell wall 30, the thread

60 12 lies against the internal side of the said wall and, as a result, forms weft thread turns lying against the said internal side. Owing to the conical shape of the shell wall 30, the thread 12 slides towards the end wall 31 so that the individual turns of the thread 12 do not tangle 65 with one another. It is advantageous to make the internal side of the shell wall relatively smooth and therefore capable of easy sliding, and to give the wall 30 a conical shape to a suitable extent.

As soon as the thread stored within the side wall 30 is of the desired length, the weft insertion nozzle 17 is operated and the thread brake 16 opens. As a result, the thread stored within the storage apparatus 15 is drawn from the said apparatus and introduced into the shed 19. For a short instant, in which it is fully extended, it extends from the front end of the nozzle 33 directly to the aperture 32 and through the insertion nozzle 17 into the shed. Owing to the continuous rotation of the end wall 31 and therefore of the cylinder 22, more thread 12 is continuously fed into the process. With the end of the weft insertion into the shed 19, the thread brake 16 again closes. Thus, another cycle of storage of weft threads in the storage apparatus 15 begins. At the next shot into the shed 17, the weft thread newly stored in the storage apparatus 15 is again drawn out through the nozzle 17.

The air passing through the nozzle 33 escapes for the greater part through the air escape apertures 38. In this way the thread 12 is forced against the internal side of the shell wall 30, which it also tends to be forced against, of course, owing to centrifugal or centripetal force developed during the turning of the shell wall 30.

FIG. 2 shows a further embodiment of the invention. In this embodiment there is again a thread 12 supplied from a supply bobbin, a cylinder arrangement 11 for determining the length of thread sections, a storage apparatus 15, a thread brake 16 and a nozzle for introducing the weft thread sections into a shed, this nozzle being designated as 17. The cylinder arrangement 11 again comprises a cylinder 22 which is surrounded by several thread turns, and also a driving surface 24. The notched element and the supply bobbin are not shown in FIG. 2. The storage apparatus 15 again comprises a shell wall 30 provided with air escape apertures 38 and an end wall 31. Also provided is an injector nozzle 33 which has a duct 34 with an extension 37 for guiding the thread 12. Through the tube 35, air is blown in from the nozzle 33. The shell wall 30 forms a driving surface 40. The end wall 31 is again provided with a central aperture 32. The line 41 designates the axis of rotation of the parts 30 and 31. In FIG. 2 a drive is shown by way of example. This can use a toothed wheel 48 which is fixed to the end wall 31 and is driven by a toothed belt 49.

The constructional example in FIG. 2 differs from the example shown in FIG. 1 in that the stationary member 42 is provided instead of the cover wall 39. The nozzle 33 is built into this stationary member. The member 42 defines with the shell wall 30 and the end wall 31 and intermediate space 43 which is approximately of the same width overall. More particularly, the wall portion 44 of the member 42 forms with the shell wall 30 an intermediate space of limited width. As a result, owing to the air flowing from the nozzle 33, an approximately uniform positive pressure is produced over the entire interior 43, so that the thread turns are applied uniformly against the wall 30 over the entire internal side of the said wall. When the weft thread is drawn from the storage apparatus 15 through the nozzle 17, the member 42 serves to guide the thread 12. In this way the thread 12 is drawn away in an orderly fashion, obviating whipping movements of the thread.

The boundary wall 45 of the member 42 which is adjacent the end wall 31 is advantageously conical in shape. The apex 46 of the cone 45 coincides with the axis of rotation 41 and is situated at a spacing from the aperture 32 of the end wall 31. Advantageously, the

member 42 is made of light metal. In this case it is easy to machine, non-rusting and can be provided with a fine and resistant surface.

In a further advantageous constructional form of the apparatus of this invention, a driving wheel 50 is used to rotate the driving surface of end wall 31. As a result, it is possible by means of the driving wheel 50 of this kind to provide a plurality of storage apparatus distributed over the periphery of the said wheel, providing the 10 possibility of the selective introduction of different kinds and types of weft thread, for example, different colors. An apparatus of this kind is illustrated in FIG. 3.

In this figure, the driving wheel 50 is mounted to be rotatable in the bearing 51. It has a conical surface or 15 means 52 over which a plurality of storage apparatus 15 are arranged. FIG. 3 shows two such apparatus 15. But there may be more, for example four or six. Each storage apparatus 15 is associated with a cylindrical arrangement 11 and a thread supply 13. The cylinders 22, storage apparatus 15, and thread supplies 13 are arranged in a similar manner to the constructional examples shown in FIG. 1 and FIG. 2. In a similar way a weft thread 12 runs from each storage apparatus 15 through a controllable thread brake 16 to a weft thread introduction nozzle (not shown). Between each storage apparatus 15 and thread brake 16 there is situated a guide eyelet 53 for each weft thread 12.

Each of the storage apparatus 15 is in continual contact with the driving wheel 50 and therefore in continuous rotational movement. The driving surfaces 24, however, can be selectively brought into contact with and removed from contact with the running surface 40 of the storage apparatus 15 associated with them in accordance with a programme. When they are not in contact, they lie against a brake 54 as is shown in the upper storage apparatus in FIG. 3. At any one time only one of the cylinders 22 is in rotation and the others are stationary. The weft thread which is conveyed at this time is introduced into the shed by the insertion nozzle allocated to it. For this purpose a control arrangement must ensure that the insertion nozzle, whose thread is conveyed, is in the prescribed position relatively to the shed for introduction of weft threads, or is moved into such a position. It is also possible to keep the cylinder arrangements 11 permanently in contact with the storage apparatus 15 and to couple the said apparatus selectively to the driving wheel 50 and uncouple them therefrom and brake them.

Each of the apparatus 11, 15 can be built on a support and can be displaced in the direction of the axes of rotation of the apparatus 11, 15, as is shown in the case of the lower apparatus by the arrow 55. By this kind of displacement, the speed of rotation of the apparatus 11, 15 relatively to the speed of the driving wheel 50 can be modified. In this way the length of the individual weft threads which come to be introduced into the shed can be varied.

This disclosure of preferred embodiments and modifications of the invention is to be interpreted as illustrative of forms the invention may take and other modifications will readily occur to those skilled in the art. The invention is not to be restricted except by the scope of the appended claims wherein the novel features desired to be protected by Letters Patent are set forth.

65 What is claimed is:

1. Apparatus for the storage of weft thread of variable length before insertion into a shed of a loom, comprising a shell wall formed as the generated surface of

a truncated cone, there being arranged at the place where the base cross-section of the truncated cone is situated an end wall which is fixed to the shell wall and which defines centrally an aperture for the exit of the stored thread, a thread feeding nozzle producing an air stream for feeding the thread to be stored, said shell wall being rotatable and provided with a plurality of apertures, said nozzle being directed toward the inner side of the shell wall to convey the weft thread toward the inner side of said shell wall to cause it to rest thereon.

2. Apparatus according to claim 1 in which said nozzle is directed towards a region of relatively small diameter of the shell wall.

3. Apparatus according to claim 1 in which in the top end cross-section of the truncated cone there is situated a stationary cover wall to which the nozzle is fixed and that the weft thread is fed through this cover wall.

4. Apparatus according to claim 1 in which a thread brake is positioned outside the centrally defined aperture through which the stored length of weft thread is passed after passing through the aperture defined in the center of the end wall.

5. Apparatus according to claim 1 in which the shell wall is provided with a plurality of apertures.

6. Apparatus according to claim 5 in which the plurality of apertures is provided by a shell wall formed from a perforated plate.

7. Apparatus according to claim 1 in which in the interior of the shell wall there is situated a stationary member which forms, with the shell wall and the end wall, an intermediate space of approximately uniform width.

8. Apparatus according to claim 7 in which the stationary member comprises at its side directed towards

the end wall a conical boundary surface, the apex of which is situated on the axis of rotation of the said rotating shell wall and at a distance from the aperture provided in the center of the end wall.

5 9. Apparatus according to claim 7 in which the nozzle is built into the stationary member.

10 10. Apparatus according to claim 7 in which the stationary member is made of light metal.

11. Apparatus according to claim 1 in which along 10 one of the external circular boundaries of the shell wall there is provided a circular driving surface which abuts against a further circular driving surface connected rigidly to a cylinder about which the weft thread is guided in several turns, the weft thread being entrained by the cylinder when the latter rotates.

12. Apparatus according to claim 1 in which a driving wheel is provided with a driving surface which is rotatable about an axis and over the periphery of which there are provided a plurality of rotatable shell walls

20 formed as the generated surface of a truncated cone, each wall with a nozzle directed towards a region of small diameter of the internal side of each shell wall, said shell walls being adapted to be driven by the driving surface, and that a rotatable cylinder for entraining and feeding one weft thread in each case can be co-rotated with each shell wall.

13. Apparatus according to claim 12 in which each cylinder can be coupled selectively each with one of the shell walls for rotation therewith.

30 14. Apparatus according to claim 12 in which the driving surface of the driving wheel is of conical shape and the shell walls can be displaced along the driving surface to regions thereof which are of different diameter.
